UNITED STATES PATENT OFFICE.

PAUL H. KRAETSCH, OF ASTORIA, OREGON.

POST-CARD TRAY.

1,211,179.

Specification of Letters Patent.

Patented Jan. 2, 1917.

Application filed November 23, 1915. Serial No. 63,065.

To all whom it may concern:

Be it known that I, PAUL H. KRAETSCH, a citizen of the United States, and a resident of Astoria, in the county of Clatsop and 5 State of Oregon, have invented a certain new and useful Improvement in Post-Card Trays, of which the following is a specification.

One of the principal objects of my invention is to provide an improved tray for receiving postcards and unmounted photographs and the like, the tray being so constructed as to retain the cards or photographs in flat extended position, and to 10 allow inspection of them without requiring their removal from the tray.

A further object of the invention is to provide an improved tray of the class described which will be extremely simple, durable, efficient in operation, and inexpensive 15 to manufacture.

With these and other objects in view which will become apparent as the description proceeds, the invention resides in the 20 construction, combination, and arrangement of parts hereinafter more fully described and claimed, and illustrated in the accompanying drawing in which like characters of reference indicate like parts throughout 25 the several figures, of which—

Figure 1 represents a view in perspective of a postcard tray constructed according to my invention. Fig. 2 represents a view in section taken longitudinally on the plane indicated by the line 2—2 of Fig. 1. Fig. 3 represents a view in perspective taken on a plane transversely of the device, on the line 3—3 of Fig. 1.

In carrying out my invention, I provide a 40 tray consisting of a bottom 5, a rear wall 6, ends 7, and a cover or top 8. The bottom 5 is preferably rectangular in shape and of an area and dimensions slightly greater than the area and dimensions of the postcards, 45 photographs, or other articles in connection with which it is used, and the rear wall and ends arise from the outer edges of the bottom, so that the cards may readily be placed within the tray. The back and sides 50 may be made integrally with each other and with the bottom 5, or if desired they may be made in a single piece and subsequently attached to the bottom. The cover 8 is shaped similarly to bottom 5, and is slightly 55 less in length than the bottom, whereby to

readily fit between the back and side walls. This cover carries an elastic band 9 which at its ends is connected with cover 8 along its medial line and adjacent the ends of the latter. The elastic band is adapted to fit around underneath the bottom 5 whereby to normally exert a tension upon the cover tending to draw it toward the bottom. The ends 7 are less than half the length of the ends of the bottom, so as not to interfere with the end portions of the elastic band 9. The height of the back and sides is such that a reasonable amount of cards may be accommodated, without giving the tray an 60 awkward or inartistic appearance.

The tray may be formed of any suitable material such as strawboard or boards of other material usually used in book-covers, covered with suitable ornamental or plain cloth, imitation or real leather, or the like, 65 and the inside of the bottom and the cover may be lined with suitable paper or if desired with the same material that the tray is 70 covered with.

In operation the cover is first removed 80 and the postcards, photographs, or other articles to be contained, are placed upon the bottom and against the back between the sides, and the cover is then placed upon the top of the stack with the elastic band 85 engaging around the bottom. The tension exerted upon the cover will at all times retain the cards in flat extended position, and will keep them in closely packed relation whereby dust and dirt will be prevented 90 from seeping in between them. The cards may be inspected readily by lifting the cover, and tilting it backwardly, and without removing the cards from the tray. In order to facilitate this operation, the forward edge of bottom 5 is provided with a recess at 10, whereby the bottommost cards may be lifted sufficiently from the bottom 5. The back and sides will operate to maintain 95 the postcards and the cover in orderly and 100 arranged position, and serve also to help maintain the cards in place in the tray. The elastic band is connected at its ends along the medial line of the cover, so that the latter may be placed on the tray with either 105 edge adjacent the rear wall.

Although I have described the preferred embodiment of my invention, I may desire to make such changes in the construction, combination, and arrangement of parts 110

thereof, as do not depart from the spirit of the invention and the scope of the appended claim.

I claim:—

5 The herein described postcard tray consisting of a bottom having a recess provided in its forward edge, a rear wall and end walls connected with the bottom, said end walls being of a length less than half the
10 length of one end of the bottom, a cover

adapted to fit between the rear wall and end walls, said cover being of a width substantially equal to the width of the upper surface of the bottom, and an elastic band connected at its ends along the medial line of the cover and extending around the bottom.

PAUL H. KRAETSCH.
